SIGNAL SELECTING CIRCUIT

Homer J. Loftis, Ironton, Ohio, assignor, by mesne assignments, to Radio Corporation of America, New York, N. Y., a corporation of Delaware

Application May 31, 1932, Serial No. 614,477

10 Claims. (Cl. 250—20)

This invention relates to a selective circuit, and more particularly to a signal selecting circuit.

Inasmuch as it is the purpose of a preselecting circuit to eliminate, as far as possible, all signals except the one that it is desired to receive, and thus aid in the selection of signals, it is an object of this invention to provide a preselector circuit of improved efficiency which will more effectively aid in the selection of signals than those commonly in use.

Another object of this invention is to provide a structure which, while providing selective efficiency, will also permit good energy transfer efficiency for that type of circuit.

Another object of this invention is to provide a structure which is simple in construction and consequently inexpensive to build.

Still another object of the present invention is to provide a signal selecting circuit having flexibility of design.

Further objects and advantages of the present invention will be apparent from the following description, reference being had to the accompanying drawing wherein several forms of the present invention are clearly shown.

In the drawing:

Fig. 1 discloses a form of signal selecting circuit utilized as a preselector circuit to couple an antenna and ground to the input of a radio receiver.

Fig. 2 discloses a modification of the circuit, utilized for the same purpose as that in Fig. 1.

With particular reference to Fig. 1, a primary inductance 10 is connected at one end to an antenna 1, and at its other end is connected to a ground 2. A secondary inductance 12 has one of its ends grounded at 16. A variable condenser 14 is connected across the inductance 12 to form a tunable resonant circuit 20 which is magnetically coupled to the antenna circuit formed by the antenna 1, inductance 10 and ground 2. Another inductance 18 is magnetically coupled with the inductance 12 of the resonant circuit 20, and connected at one end in series with an inductance 24 to ground at 26, and at the other end to an input electrode or grid 28 of a thermionic tube 40. A variable condenser 22 is connected across the inductance 18 to form a tunable resonant circuit 30. The inductance 24 is magnetically coupled with the inductance 10.

The thermionic tube 40 is indicated as including, beside the input electrode 28, an anode 32, an auxiliary grid 34, a cathode 36, and a heater 38. However, any suitable type of thermionic tube might be used. The cathode 36 is connected

to ground at 46 through a resistor 42. The potential drop across the resistor 42 provides a biasing potential between the cathode 36 and the input electrode 28. A condenser 44 connected across the resistor 42 forms a by-pass circuit for high frequency currents. The variable condensers 14 and 22 have been indicated as being controlled by a common controlling element 50, and in a preferred form of the invention would be so used.

With particular reference to Fig. 2, like reference numerals in Figs. 1 and 2 indicate similar parts. The principal difference between the two circuits resides in the fact that the inductance 24 in Fig. 1 has been replaced by a condenser 48 which performs a similar function, and is connected between the high potential or ungrounded ends of inductances 18 and 12. One end of the inductance 18 is, of course, connected directly to ground 26 instead of to ground through the inductance 24.

It is apparent to one skilled in the art that the purpose of a selective circuit, and particularly one of the type disclosed, is to tend to eliminate signals other than the one that it is desired to receive, and to allow the signal that is to be received to pass without undue attenuation. In the circuit disclosed in Fig. 1, one element of the selection is brought about by the action of the resonant circuit 20. That is, since that circuit is tunable to resonance at a particular frequency, and is coupled with the signal input circuit formed by the antenna 1, inductance 10 and ground 2, the maximum current flow around the resonant circuit 20 will be caused by the signal of the frequency to which the resonant circuit is tuned. Since the resonant circuit 30 is tuned to resonance at the same frequency by the variable condenser 22, and is coupled to the resonant circuit 20, a second element of selection is obtained through the action of the resonant circuit 30, and its cooperative action with the resonant circuit 20. However, since there is coupling between the inductance 10 and the inductance 12, and also coupling between the inductance 12 and the inductance 18 there will also be some coupling between the inductance 10 and the inductance 18.

The direct coupling between the inductance 10 and the inductance 18 somewhat impairs the selective action of the circuit as a whole, because the intermediate selective action of the resonant circuit 20 is eliminated or reduced. It has been found that the selectivity of the circuit may consequently be improved by connecting an inductance 24 in series with an inductance 18 and pro-

viding the proper amount of coupling between the inductance 24 and the inductance 10 in a proper phase relation. It is believed that the voltage induced in the inductance 34 tends to neutralize or buck the voltage induced in the inductance 18 by the field of inductance 10. The required amount of coupling between the inductances 10 and 24 may be obtained by varying the number of turns of the inductance 24, and the distance 10 between inductances 10 and 24 or their relative angular displacement. A correct phase relation between the voltage induced in the inductance 24 and that in the inductance 18 may be determined by reversal of connection to the inductance 24 or 15 the reversal of the direction of winding of the inductance 24. The resultant voltage developed between the input electrode 28 and the ground 26 is the voltage which is applied to the receiver or utilization device for amplification or utilization.

The coupling between the inductances 10 and 12, and 12 and 18 and between the inductance 10 and inductance 18, and the selective action of the resonant circuits 20 and 30 in Fig. 2 are similar to 25 those of Fig. 1. However, the condenser connected between the high potential ends of inductances 12 and 18 serves to improve the selective action of the circuit in a manner similar to that of the inductance 24 in Fig. 1. It is believed that 30 the potential applied to the high potential end of the inductance 18 from the high potential end of the inductance 20, in this modification, serves to neutralize or buck the voltage induced in the inductance 18 by the field of the inductance 10. 35 The potential thus applied to the circuit of the inductance 18 may be varied to determine the most desirable value by varying the size of the condenser 48. The phase relation in this case is fixed, but could be changed by connecting the 40 condenser 48 to the low potential end of the inductance instead of the high potential end as disclosed.

While I have indicated and described several 45 systems for carrying my invention into effect, it will be apparent to one skilled in the art that my invention is by no means limited to the particular organizations shown and described, but that many modifications may be made without departing from the scope of my invention as set forth 50 in the appended claims.

What is claimed is as follows:

1. A preselector circuit for a signal selecting device, comprising in combination, a plurality of magnetically coupled tunable resonant circuits, 55 an inductance magnetically coupled with one of said resonant circuits, a second inductance connected to another one of said resonant circuits and coupled with the first mentioned inductance in a manner to reduce coupling between said first 60 inductance and the last named resonant circuit.

2. A preselector circuit for a signal selecting device, comprising in combination, a plurality of magnetically coupled tunable resonant circuits, an inductance magnetically coupled with one of 65 said resonant circuits, and a capacity for coupling said one circuit with a second of said tunable circuits to minimize coupling between said inductance and said second circuit.

3. A preselector circuit for a signal selecting 70 device, comprising in combination, a plurality of magnetically coupled tunable resonant circuits, an inductance magnetically coupled with at least 75 two of said resonant circuits, and means for neutralizing the coupling between said inductance and one of said two resonant circuits.

4. A selective signal input circuit for a radio receiving device, including in combination, an antenna circuit, a tunable resonant circuit coupled with said antenna circuit, a second tunable resonant circuit magnetically coupled with the first mentioned resonant circuit, said antenna circuit and said second circuit being normally coupled, and means coupling said second resonant circuit with said antenna circuit and tending to neutralize the normal coupling therebetween.

5. In a selective circuit for a radio device, the combination including, a primary circuit, a secondary circuit, a third circuit coupled with said secondary circuit and said primary circuit, and means coupling said third circuit to said primary circuit in a sense opposed to the first coupling therebetween for improving the operation of said selective circuit.

6. In a radio receiver, a pre-selector network comprising a pair of cascaded resonant oscillation circuits, said circuits being magnetically coupled, means for similarly tuning said coupled circuits to a common frequency, a source of signal energy magnetically coupled to each of said coupled circuits, and means connected to the second of said coupled circuits, electrically associated with at least a portion of the network preceding it in such a manner that the magnetic coupling between said source and said second circuit is decreased.

7. In a radio receiver, a pre-selector network comprising a pair of cascaded resonant oscillation circuits, said circuits being magnetically coupled, means for similarly tuning said coupled circuits to a common frequency, a source of signal energy magnetically coupled to each of said coupled circuits, and means including a condenser connected to the second of said coupled circuits, electrically associated with at least a portion of the network preceding it in such a manner that the magnetic coupling between said source and said second circuit is decreased.

8. In a radio receiver, a pre-selector network comprising a pair of cascaded resonant oscillation circuits, said circuits being magnetically coupled, means for similarly tuning said coupled circuits to a common frequency, a source of signal energy magnetically coupled to each of said coupled circuits, and means including a coil, connected to the second of said coupled circuits, 120 electrically associated with at least a portion of the network preceding it in such a manner that the magnetic coupling between said source and said second circuit is decreased.

9. In combination, a signal selector network 130 comprising at least two cascaded resonant circuits tuned to a common signal frequency, said circuits being reactively coupled, a source of signal energy reactively coupled to each of said coupled circuits, and reactive means, connected 135 to the second of said coupled circuits, electrically associated with at least a portion of the network preceding the second circuit in such a manner that the effect of the reactive coupling between said source and said second circuit on the selectivity of the network is decreased.

10. In a network as in claim 9, said reactive 140 couplings being magnetic, and said reactive means consisting of a condenser connected between the high signal potential sides of the two coupled circuits.
